UNITED STATES PATENT OFFICE.

HERMANN KAMP, OF BARMEN, GERMANY.

MOISTENER.

1,419,504.

Specification of Letters Patent. Patented June 13, 1922.

Application filed May 23, 1914. Serial No. 840,565.

(GRANTED UNDER THE PROVISIONS OF THE ACT OF MARCH 3, 1921, 41 STAT. L., 1313.)

To all whom it may concern:

Be it known that I, HERMANN KAMP, a subject of the King of Prussia, German Emperor, residing at Barmen, in the Kingdom 5 of Prussia, German Empire, have invented certain new and useful Improvements in a Moistener, of which the following is a specification.

This invention relates to a moistener of 10 that type, in which the water or other liquid from the reservoir is supplied to the sponge or other porous mass by means of capillary channels. According to the invention the porous mass is mounted in a casing of elastic 15 material which serves at the same time as stopper for the lower end of the water reservoir. The lower edge of said stopper is flat and situated somewhat back of the outer surface of the porous mass, so that, if the 20 moistener is placed on a surface to be moistened the edge of the elastic stopper adheres on said surface and air-tightly closes the moistener. The air contained in the moistener is forced back into the reservoir, so 25 that if the moistener is lifted the water is drawn into the porous mass in consequence of the vacuum formed in the cavity of the stopper.

The cavity provided between the porous 30 mass and the water reservoir prevents the water from leaking from the reservoir.

In the accompanying drawings the invention is shown by way of example:

Fig. 1 is a section through the moistener; 35 Fig. 2 is an elevation of the same;

Fig. 3 is a top view of the sponge holder.

The improved moistener comprises in combination a water reservoir *a*, a stopper *b* of elastic material and a sponge *c* of india-rubber or other porous material. The open 40 lower end of the reservoir *a* is closed by the

elastic stopper *b*. In the upper end of the stopper *b* several capillary channels *d* are provided. The stopper *b* of elastic material has a cavity in its lower end which is filled 45 by the sponge *c*. The surface of the sponge slightly projects over the lower edge *e* of the stopper. Between the sponge and the upper end of the stopper *b* an air chamber is arranged.

If the moistener is used, its lower end is 50 pressed on the surface to be moistened, so that the edge *e* of the stopper *b* comes in contact with the surface and airtightly closes the interior of the moistener so that when the device is pressed close to the work, the cup and with it the sponge is compressed and thereby the air contained in the air chamber is forced up into the water reservoir *a*, whereby the pressure in this reservoir back of the 55 water is increased. If the moistener is lifted off the surface water is forced out of the reservoir by an excess of pressure back of the water so that the sponge is moistened.

I claim:

An improved moistener comprising in combination a water reservoir open at the lower end, a stopper of elastic material in the lower end of said reservoir having capillary channels in its upper part and a cavity 70 in its lower part which gets narrow towards said capillary channels, a flat lower edge of said elastic stopper, and a sponge of porous material in the large lower part of the cavity of said stopper, substantially as described 75 and shown and for the purpose set forth.

In witness whereof I have hereunto set my hand in the presence of two witnesses.

HERMANN KAMP. [L. S.]
